UNITED STATES PATENT OFFICE

99,776

DESIGN FOR A TEXTILE FABRIC

Oscar J. Cahn, New York, N. Y.

Application February 26, 1936, Serial No. 61,358

Term of patent 3½ years

To all whom it may concern:

Be it known that I, Oscar J. Cahn, a citizen of the United States, residing at New York city, county and State of New York, have invented a new, original, and ornamental Design for a Textile Fabric, of which the following is a specification, reference being had to the accompanying drawing, forming part thereof.

The figure is a plan view of a textile fabric showing my new design.

The design comprises diagonal stripes on a rough ground, the stripes being formed by over-stitching, presenting a broken appearance by alternating dull thread with shiny thread, and the whole cloth has a superimposed hairy surface appearance.

I claim:

The ornamental design for a textile fabric substantially as shown and described.

OSCAR J. CAHN.
